US0D1022622S

(12) **United States Design Patent** (10) **Patent No.:** **US D1,022,622 S**
(45) **Date of Patent:** ** *Apr. 16, 2024

(54) **FOOD STORAGE CONTAINER**

(71) Applicant: **Xiaohui Chen**, Nanchang (CN)

(72) Inventor: **Xiaohui Chen**, Nanchang (CN)

(73) Assignee: **Xiaohui Chen**, Nanchang (CN)

(*) Notice: This patent is subject to a terminal disclaimer.

(**) Term: **15 Years**

(21) Appl. No.: **29/858,925**

(22) Filed: **Nov. 4, 2022**

(51) LOC (14) Cl. **07-07**
